PORTABLE RUG OR CARPET CLEANER

Filed Nov. 24, 1947

INVENTOR,
RALPH J. WILLIS

BY
Wm. H. Dean
AGENT

UNITED STATES PATENT OFFICE

2,610,343

PORTABLE RUG OR CARPET CLEANER

Ralph J. Willis, Oceanside, Calif.

Application November 24, 1947; Serial No. 787,761

4 Claims. (Cl. 15—92)

1

My invention relates to a portable rug or carpet cleaner and the objects of my invention are:

First, to provide a cleaner of this class which very efficiently beats and cleans rugs and carpets without unduly wearing or abrading the surface of the same;

Second, to provide a carpet cleaner of this class which very rapidly cleans a considerable area of carpet space;

Third, to provide a cleaner of this class in which a plurality of rotating rods each supports a plurality of resilient rings thereon which actually forcefully engage the surface of the carpet in a rolling motion which thoroughly but gently cleans fine rugs and carpets;

Fourth, to provide a cleaner of this class which is operated in substantially a similar manner to a manual operation of a conventional carpet sweeper during which time the constant operation of the beaters is accomplished by a motor so that particularly dirty portions of a rug may be concentrated upon without moving the cleaner over the rug numerous times;

Fifth, to provide a cleaner of this class which is particularly adapted for use in production rug or carpet cleaning; and

Sixth, to provide a rug and carpet cleaner of this class which is very simple and economical of construction, efficient in operation and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon forming a part of this application in which: Figure 1 is a front elevational view of my rug and carpet cleaner showing portions thereof broken away and in section to amplify the illustration; Fig. 2 is a fragmentary bottom plan view thereof; Fig. 3 is a fragmentary side elevational view of my rug and carpet cleaner and Fig. 4 is an enlarged fragmentary sectional view taken from the line 4—4 of Fig. 1.

Similar characters of reference refer to similar parts and portions throughout the several views of the drawing.

The frame 1, motor 2, shaft 3, bearing 4, pulleys 5 and 6, belt 7, beater shafts 8, 9 and 10, shaft end plates 11 and 12, beater rings 13, rollers 14 and 15, caster 16, screw 17, caster base 18, handle 19, shaft 20 and the plate 22 constitute the prin-

2

cipal parts and portions of my rug and carpet cleaner.

The frame 1 is substantially arcuate in cross section as shown in Fig. 3 of the drawing, being enclosed at its upper side and open at its lower side. The motor 2 is supported on the upper side 1a of the frame 1 and the shaft 3 extending therefrom, passes through the bearing 4 at one end of the casing 1. Secured to the outer end 10 of the shaft 3 is the pulley 5, engaging the belt 7 which passes over the pulley 6 on the shaft 20. This shaft 20 is journaled in one end of the frame 1 and fixed to the inner end of this shaft 20 is the shaft end plate 11 which opposes the shaft end plate 12 fixed on the shaft 20 journaled in the opposite end of the frame 1, all as shown best in Figs. 1 and 2 of the drawing. Secured to these end plates 11 and 12 and extending therebetween are the shafts 8, 9 and 10. These beater shafts 8, 9 and 10 support the resilient rings 13 loosely threaded thereon, as shown in Fig. 4 of the drawing. These rings are considerably larger in diameter than the outside diameter of the shafts 8, 9 and 10 and are arranged to move freely about 25 said shafts 8, 9 and 10. The plate 22 serves to interconnect the middle portions of the three shafts 8, 9 and 10 as shown best in Fig. 2 of the drawing. It will be here noted that the rings 13 may be made of rubber or any other suitable 30 flexible or resilient material as desired and that centrifugal force acting on these beater rings 13 causes the same to be extended laterally of the shafts 8, 9 and 10 toward the rug A as shown by dash lines in Fig. 3 of the drawing when the shaft 20 is rotated in connection with the pulley 6 by the belt 7 over the pulley 5 driven by the shaft 3 of the motor 2. The rings 13 are thus yieldable in direction radially of each of said rings. The rollers 14 and 15 and caster 16 provide for portability of the rug or carpet cleaner while the screw 17, screw threaded in the rearwardly extending boss 1b of the frame 1, provides for the vertical adjustment of the caster base 18 as shown in Fig. 3 of the drawing. This caster base 18 is a resilient plate adapted to be deflected by downward extension of the end 11a of the screw 17 bearing on the upper surface of said caster base 18. Vertical adjustment of the rear end of the frame 1 tends to adjust the spaced relationship of the shafts 8, 9 and 10 from the rug A when rotating.

The operation of my rug and carpet cleaner is substantially as follows:

When the motor 2 is rotating the shaft 3, the 55 pulleys 5 and 6 engaged by the belt 7 drive the

shaft 20 which rotates the shaft end plate 11 engaging the beater shafts 8, 9 and 10 which are secured to the shaft end plate 12 at their opposite ends and this shaft end plate 12 is secured to the shaft 20 journaled in the casing 1 as hereinbefore described. As the beater shafts 8, 9 and 10 rotate about the axis of the shaft 20, the rings 13 are centrifugally extended and engage the upper surface of the rug A in their side to side relationship to each other. These rings 13 are resilient rings and provide a rolling and beating motion at the upper surface of a carpet or rug which very efficiently removes the dust and foreign matter from the nap of the rug or carpet as the case may be. It will be here noted that the rings 13, due to their flexible and resilient character, and due to their loosely supported condition, operate as flippers, providing a novel rug beating and cleaning action. The upper opposed side of the frame 1 prevents dust from rising directly above the rug or carpet cleaner and the entire cleaner is manually maneuvered over a rug or the like by means of the handle 10 and rollers 15 and 14 and caster 16. Vertical adjustment of the beater rings 13 relatively to the upper surface of the rug A is accomplished by vertical adjustment of the screw 17 in the boss 1b of the frame 1 which causes deflection of the caster base 18 and consequent vertical movement of the axis 30 of the shaft 20. The plate 22 forms a connector for the shafts 8, 9 and 10 preventing centrifugal force from separating the same at their middle portions.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a portable rug or carpet beating machine of the class described, the combination of a plurality of spaced substantially parallel shafts, means mounting said shafts for rotation about an axis centrally of said a plurality of shafts and a plurality of flexible resilient rings of a readily yieldable material on said shafts having openings therein equal to several diameters of said shafts, said flexible rings being yieldable in directions radially of each of said rings.

2. In a portable rug or carpet beating machine of the class described, the combination of a plurality of spaced substantially parallel shafts, means mounting said shafts for rotation about an axis centrally of said a plurality of shafts and a plurality of flexible resilient rings of a readily yieldable material on said shafts having openings therein equal to several diameters of said shafts, said flexible rings being yieldable in directions radially of each of said rings and said rings loosely positioned on said shafts and adapted to move laterally thereof, plates at opposite ends of said shafts for connecting the same together and a central shaft connected with said plates having its axis substantially centrally of said a plurality of shafts.

3. In a portable rug or carpet beating machine of the class described, the combination of a plurality of spaced substantially parallel shafts, means mounting said shafts for rotation about an axis centrally of said a plurality of shafts and a plurality of flexible resilient rings of a readily yieldable material on said shafts having openings therein equal to several diameters of said shafts, said flexible rings being yieldable in directions radially of each of said rings and said rings loosely positioned on said shafts and adapted to move laterally thereof, plates at opposite ends of said shafts for connecting the same together and a central shaft connected with said plates having its axis substantially centrally of said a plurality of shafts and a frame in which said central shaft is rotatably mounted and a motor on said frame for rotating said central shaft, said frame being enclosed at the upper side over said a plurality of shafts.

4. In a portable rug or carpet beating machine of the class described, the combination of a plurality of spaced substantially parallel shafts, means mounting said shafts for rotation about an axis centrally of said a plurality of shafts and a plurality of flexible resilient rings of a readily yieldable material on said shafts having openings therein equal to several diameters of said shafts, said flexible rings being yieldable in directions radially of each of said rings and said rings loosely positioned on said shafts and adapted to move laterally thereof, plates at opposite ends of said shafts for connecting the same together and a central shaft connected with said plates having its axis substantially centrally of said a plurality of shafts and a frame in which said central shaft is rotatably mounted and a motor on said frame for rotating said central shaft, said frame being enclosed at the upper side over said a plurality of shafts and rollers for supporting said frame on the upper surface of a rug, one of said rollers being vertically adjustable relative to said frame for adjusting the elevation of said rings on said a plurality of shafts from the upper surface of a rug or the like.
